[57] CLAIM

The ornamental design for a soap bar holder, as shown and described.

DESCRIPTION

FIG. 1 is a top, front, and right side perspective view of a soap bar holder showing our new design;

FIG. 2 is a top plan view thereof, the bottom being a mirror image of that shown;

FIG. 3 is a front elevational view thereof, the rear being a mirror image of that shown;

FIG. 4 is a right side elevational view thereof, the left side being a mirror image of that shown; and

FIG. 5 is a vertical cross-sectional view thereof, taken long line 5—5 of FIG. 2.
